UNITED STATES PATENT OFFICE.

HENRY JACOBS, OF ST. LOUIS, MISSOURI.

DESIGN FOR A CLOCK-CASE.

SPECIFICATION forming part of Design No. 35,832, dated April 1, 1902.

Application filed December 31, 1901. Serial No. 87,973. Term of patent 3½ years.

To all whom it may concern:

Be it known that I, HENRY JACOBS, a citizen of the United States, residing at St. Louis, in the State of Missouri, have invented and produced a new and useful Design for a Clock-Case, of which the following is a specification.

The herein-described design has relation to a clock-case to be cast or otherwise formed as an article of manufacture, and is illustrated in the drawings attached to and forming part hereof.

Figure 1 is a front elevation of a clock-case formed according to my design. Fig. 2 is a side elevation of Fig. 1.

As shown in the drawings, the design as a whole is a clock-case globular structure above, merging into a pedestal-shaped lower extension supported upon a flat base.

The leading or material feature of my design consists of the general configuration of the clock-case, whose main portion, in which the clock-works are contained, is an approximately spherical body having at the front side thereof an aperture for the retention and exhibition of the clock-face and whose lower portion is a pedestal of polygonal cross-section whose outer faces are extended above in converging planes and merged with the surfaces of the globular body, making surface inclinations and outlines of pleasing effect.

The general pleasing effect of the design is heightened by raised meridians upon the globular portion of the structure, extended into raised strips or corner projections following

the angles or meeting edges of the surfaces of the pedestal structure down to the base, and by a relatively broad and similarly-raised band, as an equatorial zone, about the globular portion, interrupted in front by a raised marginal wall about the clock-face opening and at the rear by an access-opening to the interior. The presence of these meridians and raised corner-strips gives the general surface the effect of paneling, which is an incidental but pleasing feature of the general design and may be extended into further detail by intervening raised lines of lesser height and width, giving thereby the suggestion of systematic detail without sacrifice of the larger effects. I also introduce openings in one or more of the lower vertical faces of the pedestal above the base.

As an effect of finish and completeness to the whole I surmount the globular portion of the clock-case with an ornamental figure, such as the pagoda or storied octagonal tower shown in the drawings.

Having described my invention, what I claim as new, and desire to secure by Letters Patent, is—

The design for a clock-case as herein shown and described.

In testimony whereof I have hereunto set my hand in presence of two subscribing witnesses.

HENRY JACOBS.
